UNITED STATES PATENT OFFICE

JAMES R. CALDWELL, OF UPPER SANDUSKY, OHIO, ASSIGNOR OF ONE-HALF TO LEWIS B. ASHMUN, OF UPPER SANDUSKY, OHIO.

TWINE-CUTTER.

1,031,772.

Specification of Letters Patent.

Patented July 9, 1912.

Application filed October 10, 1910. Serial No. 586,283.

To all whom it may concern:

Be it known that I, JAMES R. CALDWELL, a citizen of the United States, residing at Upper Sandusky, in the county of Wyandot and State of Ohio, have invented certain new and useful Improvements in Twine-Cutters, of which the following is a specification, reference being had to the accompanying drawings.

10 This invention is an improved device to be worn on a finger, like a ring, and used for cutting twine, thread or other like material, the device being especially adapted for use by persons who tie up bundles and packages, and the said device consisting in the construction and arrangement of parts hereinafter described and claimed.

In the accompanying drawings—Figure 1 is a perspective view of a twine cutter 20 constructed in accordance with my invention. Fig. 2 is a side view of the same. Fig. 3 is a perspective view of a modified form of my invention. Fig. 4 is a perspective view of another modified form of 25 the same. Fig. 5 is a side elevation of another modified form of my twine cutter.

In accordance with my invention, I provide a ring which is adapted to be placed and worn on a finger, usually the little 30 finger, and is provided with a knife blade which may be employed for cutting thread, cord, or the like material.

In the form of my invention shown in Fig. 1, the ring 1, which is preferably a casting, but which may be made in any suitable manner, and of any suitable material, is provided on its upper side with a stud 2, which is provided with a kerf, 3, which extends transversely thereof, and 40 parallel with the ring. From the inner side of the ring project a pair of bearing arms, 4, 5, to respectively bear on the upper and lower sides of the third finger, and hence brace and support the ring so that 45 the latter will not turn on the little finger on which it is worn. These arms are made of spring material so that the space between them may be varied, and hence enable the device to be used by persons of different 50 size. Moreover the spring arms, by pressing on one finger, secure the device from slipping on the finger which is in the ring 1. A knife blade 6, which is preferably made of highly tempered steel, and which

is curved longitudinally, has the inner end 55 of its shank secured in the kerf 3 of the stud 2 as by means of pins, rivets or the like, 7. The cutting edge 8 of the knife blade is concave, and is ground on opposite sides, the blade terminating in a blunt end, 60 as shown. This knife blade projects outwardly from the stud 2 and hence over the little finger of the wearer of the device, where it is entirely out of the way, and will not at all interfere with the movements of 65 the wearer in tying a bundle or package, of any kind, and by a simple single movement, may be employed to cut the cord after the bundle has been tied, as will be understood.

In the form of my invention shown in Fig. 3, a ring is made from a single piece of sheet metal, as at 9, which is bent in the required form and is off-set as at 10, at the outer side of the ring, the terminals 11 of 75 the strip of material from which the ring is formed being disposed in parallel relation and projecting from the upper side of the ring, and by reason of the off-sets 10, being disposed somewhat in rear of the 80 front side of the ring. The said off-set portions 10 of the ring are curved on their rear sides as at 12 to adapt the ring to fit at the inner end of the little finger of the wearer. The blade 13 has the inner end 85 of its shank disposed between the upstanding terminals of the ring, and secured in place as by means of rivets or other suitable devices 14. The blade is curved longitudinally, projects forwardly over the little 90 finger of the wearer, the portions 11 of the ring spacing the blade sufficiently from the finger, and the cutting edge of the blade is concave, and is ground on opposite sides and made sufficiently sharp to enable it 95 by a slight stroke to cut a cord after a package has been wrapped.

In the form of my invention shown in Fig. 5, the ring 15 has on its under side, the rearwardly extending blade 16 which 10 curves inwardly and rearwardly, and disposes its hollow or curved cutting edge 17 opposite the inner side of the hand, at the inner end of the little finger.

I claim:

As a new article of manufacture, the herein described twine cutter consisting of a finger ring formed on one side with later-

105

ally projecting bearing arms spaced from each other, and a blade connected to said ring and extending out over and beyond the side of the ring, the blade extending in a direction opposite to the bearing arms and being formed with a cutting edge and terminating in a blunt extremity.

In testimony whereof I hereunto affix my signature in the presence of two witnesses.

JAMES R. CALDWELL.
